CLAIM

The ornamental design for a display screen or portion thereof with animated user interface.

DESCRIPTION

FIG. 1 is a first image in a sequence for a display screen or portion thereof with animated user interface showing our new design in a first environment.

FIG. 2 is a second image of the sequence of FIG. 1.

FIG. 3 is a third image of the sequence of FIG. 1.

FIG. 4 is a fourth image of the sequence of FIG. 1; and, FIG. 5 depicts the display screen or portion thereof with animated user interface of FIG. 4 in a second environment. The appearance of the animated images sequentially transitions between the images shown in FIGS. 1-5. The process or period in which one image transitions to another forms no part of the claimed design.
